UNITED STATES PATENT OFFICE.

LEE L. CARSON, OF CHELSEA, OKLAHOMA.

BROODER.

1,111,947.

Specification of Letters Patent. Patented Sept. 29, 1914.

Application filed April 29, 1913. Serial No. 764,399.

To all whom it may concern:

Be it known that I, LEE L. CARSON, citizen of the United States, residing at Chelsea, in the county of Rogers and State of Oklahoma, have invented certain new and useful improvements in Brooders, of which the following is a specification.

My invention relates to brooders for young chicks, and the like, and especially to the 10 type known as out-door brooders.

The object of the invention is to provide an improved hover construction, having novel features of circulation and ventilation, and to provide an improved heating arrangement for supplying warm air to the hover.

In order that my invention may be readily understood, reference is had to the accompanying drawings, forming part of this 20 specification, and in which:

Figure 1 is a front elevation of the complete brooder; Fig. 2 is a transverse section on the line 2—2 of Fig. 1; Fig. 3 is a plan view of the hover and associated parts on 25 an enlarged scale, the walls of the brooder being shown in section; Fig. 4 is a central, longitudinal, vertical section through the apparatus shown in Fig. 3; Fig. 5 is a vertical transverse section taken substantially on the line 5—5 of Fig. 3, looking in the direction 30 of the arrow, and showing a lamp in position; Fig. 6 is a horizontal section taken substantially on the line 6—6 of Fig. 4; and, Fig. 7 is a vertical section through part of 35 the heating drum and smoke flue, parts being shown in elevation.

Referring to the drawings in detail, the brooder comprises a house or coop 1, having a slanting hinged roof 2, and provided in 40 its front walls with upper and lower hinged windows 3 and 4. Ventilation openings 3^a may be provided in the end walls of the brooder if desired. The brooder is divided into upper and lower compartments by 45 means of a floor 5, on which the hover is supported, and the lower compartment is provided with a floor 6, preferably supported slightly above the level of the ground. Communication between the upper and 50 lower compartments of the brooder is ef-

fected by means of the usual trap-door and ladder (not shown).

7 designates the hover as a whole, and from the top thereof extends an elbow 8 of a smoke flue, provided with a damper 9, 55 and connected with a pipe 10 which extends out through the end wall of the brooder and terminates in a short cross-pipe 11 and T-heads 11^a which serve to protect the lamp from wind. 60

In one end wall of the brooder house is a door 12, extending at least as high as the level of the floor 5, and extending across the brooder between the floors 5 and 6, is a transverse partition 13. Such partition and 65 the end and side walls of the brooder form a housing in which the lamp box is located. Such housing has a removable top 5^a, in the plane of the floor 5, which top may be conveniently supported by the partition 13. 70

Within the housing just described is located a lamp box 15, preferably formed of sheet metal, and preferably insulated from the partition 13, and from the floor 6, by means of a layer of asbestos 14. The lamp 75 box has a top 16 and a door 17, through which the lamp may be inserted. The door 17 is provided with an opening 18 covered with a piece of mica 18^a, through which the lamp may be seen. 80

It will be observed that the lamp box is spaced from the sides, top and back of the housing to provide air passages 19 and 20 which surround the lamp box on all sides. Draft tubes 21 preferably extend through 85 the floor 6 and project upwardly into the lamp box at each side thereof. An air conduit 22 passes through and is rigidly supported by the door 12 in such a position that its inner end abuts against the door 17, and 90 registers with the window opening 18 therein. Said conduit is also provided with a lateral opening 23 (see Fig. 6) which establishes communication between the conduit and the space 19. Such opening is controlled by an adjustable slide 24, which projects from the outer end of the conduit. 95

The lamp box has a centrally disposed opening 25 in its top wall 16, and from such opening extends a conduit 26 to a heating 100

drum 27, located in the hover. Such drum is of flat, cylindrical form and is suspended in a horizontal position by means of brackets 28 secured to the rigid top 29 of the hover, 5 a sheet of asbestos 30 being interposed if desired. The heating drum is suspended below the top of the hover to provide an air space 31 and a conduit 32, open at both ends, extends vertically and centrally through the 10 drum and establishes communication between the air space 31, above the drum, and the chick space between the drum and the floor 5. Surrounding the drum, but spaced apart therefrom, is an annular rigid wall 33 15 preferably formed of sheet metal, and also preferably covered with a protecting layer 35 of asbestos. Such rigid wall does not extend to the floor 5, but is supported by means of legs 34, 36, and 37, the legs 34 and 20 37 being comparatively wide. The leg 37 has an opening 38 therethrough which communicates with a ventilation duct 39 formed by a semi-cylindrical piece of sheet metal 40, preferably protected by asbestos 35. 25 Surrounding the rigid wall 33 of the hover and the legs 36 is a curtain 41 which is secured at its top edge to the top of the hover, and has its lower edge reaching substantially to the floor 5. This curtain may 30 be cut away at each side of the leg 34, and also at each side of the flue 40. Extending through the rigid wall 33 of the hover and surrounding the conduit 26 is a second conduit 42, the lower end of which 35 rests upon and is supported by the removable top 5^a of the lamp box housing. This conduit may be surrounded by a wire screen 43; so as to prevent the chicks from coming 40 in contact therewith. Connected with the conduit 42 and extending on each side thereof are branch conduits 44, which pass downwardly through the cover 5^a of the housing and communicate with the space 20 between such housing and the lamp box. 45 The operation is as follows: A lamp 45 being placed in the lamp box 15 immediately under the opening 25, with its chimney 46 projecting into such conduit, the products of combustion pass upwardly 50 through the conduit 26 and into the heating drum 27. From thence they pass out through the pipes 8, 10, and 11, and are controlled by means of the damper 9. Air for the lamp is supplied through the tubes 55 21, and the chimney 46 is provided with the usual mica window, through which, and the window 18, the operation of the lamp may be observed without opening the door. As shown in Fig. 5, the lamp chimney 46 60 is provided with a wire screen top, 47, and this acts as a safety device to extinguish the lamp should the screen become clogged with soot, by reason of a smoky flame. Fresh air also passes through the lateral opening 23 65 and thence through the passages 19 and 20,

around and over the lamp box and is thereby warmed. From the housing this warmed air passes upwardly through the conduits 44 and 42 into the space between the heating drum and rigid wall of the hover, where it 70 is confined by such walls and the curtain. It will be noted that the top 29 of the hover is without openings, and hence the escape of the warm air is prevented. Inside the hover the air circulates through the central 75 conduit 32, the space 31 and the annular space around the drum, thus maintaining a uniform temperature in the chick space underneath the drum. Excess air or the foul and cooler air passes out through the opening 38 which, it will be noted, is located near the floor of the hover. It will be observed that the lamp box is of comparatively large area, and that the in-coming air passes around all four sides and the top of it, thus 80 insuring the sufficient heating of such air.

It will thus be seen that I have provided a brooder of simple construction having many desirable features as to the heating and circulation of the air, and it is thought 90 that the many advantages of the arrangement will be readily appreciated without further discussion.

What I claim is:

1. In a brooder, a heater comprising a 95 metallic lamp box, a housing therefor spaced therefrom on sides and top, a vertical conduit communicating with the interior of said lamp box and serving to convey the products of combustion, a second conduit surrounding 100 the first, and a pair of branch conduits connected at one end with said second conduit and communicating at their other end at separated points with the space between the top of the lamp box and housing, whereby 105 said second and branch conduits serve to convey air heated by passage over said lamp box.

2. In a brooder, a hover, a heating drum therein, a metallic lamp box, an outer housing entirely surrounding said lamp box and spaced therefrom on all four sides and top to provide air passages, a conduit extending upwardly from the interior of said box to said heating drum for conveying the products of combustion, a second conduit inclosing the first, and extending upwardly from the top of said housing and thence laterally to said hover, said second conduit communicating with the space between said housing and lampbox, means for supplying air through the bottom of said lamp box to support combustion, and means for supplying air to the space between said lamp box and housing, at one side of the latter, whereby 120 incoming air is caused to circulate around and over the said lamp box, before passing through said second circuit to said hover.

3. In a brooder, a heater comprising a lamp box, and a housing therefor, spaced 130

therefrom, a door in said housing, the wall of said lamp box adjacent said door having a window, a conduit carried by said door and registering with the window in said lamp box, whereby the interior of said box may be seen by looking through said conduit and window, said conduit also having a lateral opening communicating with the

space between said lamp box and housing, whereby air is supplied to said space. 10

In testimony whereof I have affixed my signature in presence of two witnesses.

LEE L. CARSON.
